UNITED STATES PATENT OFFICE.

JOHN DONATH, OF CHICAGO, ILLINOIS.

CHIME-WHISTLE.

No. 913,707.

Specification of Letters Patent.

Patented March 2, 1909

Application filed June 23, 1908. Serial No. 439,944.

To all whom it may concern:

Be it known that I, JOHN DONATH, a citizen of the United States, residing at Chicago, county of Cook, and State of Illinois, have 5 invented certain new and useful Improvements in Chime-Whistles, of which the following is a specification.

My invention relates to chime-whistles and particularly to that class of chime-whistles adapted for use as signal devices for automobiles, boats and the like.

The object of my invention is to provide a chime-whistle as mentioned, in which the members or whistles of which the device is 15 composed may be sounded independently or chimed, that is sounded simultaneously as the operator desires.

A further object is to provide a device as mentioned, which will produce a rich and 20 full tone when sounded, and to provide a device which may be easily and quickly operated.

A further object of my invention is to provide a device as mentioned, which will occupy 25 a comparatively small space and which will be strong, durable, simple of construction, hence of low cost to manufacture.

Other objects will appear hereinafter.

With these objects in view, my invention 30 consists generally in a plurality of whistles of novel construction graduating in size, hence in tone when sounded, thereby producing the chime, said whistles being suitably mounted or arranged in a suitable wind-chamber member the whole being arranged or inclosed in a suitable casing.

My invention further consists in novel and simple means for sounding, that is admitting wind into one or a number of whistle-members 40 at one time or into all whistle-members simultaneously as desired.

My invention further consists in certain details of construction and arrangements of parts all as will be hereinafter fully described 45 and particularly pointed out in the claim.

My invention will be more readily understood by reference to the accompanying drawings forming a part of this specification, and in which,

50 Figure 1 is a front elevation of my device in its preferred form, the front portion of the casing members being removed, Fig. 2 is a horizontal longitudinal section taken on the line $x-x$ of Fig. 1, Fig. 3 is a vertical transverse section taken on the line $y-y$ of Figs. 1 and 2, and Fig. 4 is a detail vertical longitudinal section taken on substantially the line $z-z$ of Fig. 3.

Referring now to the drawings, 1 indicate a plurality of pairs of vertically disposed, 60 preferably cylindrical pipes or tubes, closed at their upper ends. 2 indicate the shorter pipes and 3 the longer of said pairs of pipes 1. The plane of the lower ends 4 of said pipes 2 and 3, is at an oblique angle as clearly shown 65 in Figs. 1 and 2. Each of the pairs of pipes 1 are suitably secured preferably by soldering the rear or lower portions 5 to a flattened tubular member 6. Said member 6 is preferably rectangular in cross section and formed 70 so that the upper and lower walls taper toward their outer or attached ends forming an elongated outlet 7 the vertical walls of said member tapering toward the other end forming a slightly larger inlet 8 as shown in 75 the Figs. 3 and 4. The members 6 are suitably secured in oblique position at their outer or outlet ends 7, preferably by soldering, in slots 9 in a wind-chamber member 10, said member being of any suitable shape preferably 80 square in cross section as shown in the drawings. The members 6 are so positioned in said member 10 that wind passing through them will be guided so as to impinge upon the outer edges 11 of the members 2 and 3 85 thus producing the whistling sound. The ends 8' of the guide members 6 lie in a vertical plane. Resting against each of said ends 8' and normally closing the openings 8 is a vertically disposed plate-like wind shut-off 90 member 12 preferably rectangular in shape. Each of the members 12 is provided with a slot or perforation 13, each of said perforations being similar in shape to its respective end 8' of the member 6 and with which it is 95 adapted to register.

Vertically disposed and extending through slots in the upper wall 10' of the member 10 and suitably secured one to each of the upper edges 14 of the members 12, are rods 15. 100 The rods 15 are mounted for vertical reciprocation in brackets 16 secured, preferably soldered, to the pipes 2 and 3. Each of said members 15 is provided with a horizontal off-set portion 17, all of said off-set portions 105 17 lying in the same horizontal plane as clearly shown in Fig. 3. The rods 15 project through the upper portion of the casing and are provided with buttons 18. Coil springs 27 interposed between the horizontal off-set 17 and the horizontal upper portion 10' of the chamber member 10, nor-

mally hold as stated, the slotted shut-off members 12 in position to close the inlets 8 of the members 6.

5 19 indicates the end of a wind-supply pipe leading to the wind-chamber 10, the other end of said pipe being connected with a suitable wind-supply source.

10 It is obvious that in order to sound a pair or pairs of whistles all that is necessary is to depress the button or buttons 18 of the certain determined whistles to be sounded which brings the slot 13 of the plate 12 to register with the inlet 8 of the member 6 leading to that certain whistle or whistles 15 and thus admitting wind sounding the same. In order to facilitate sounding all the whistles simultaneously, I provide a sort of bell-crank lever 20. Said lever is suitably mounted in brackets 21 secured to the upper portion 10' of the wind-chamber member 10. 20 The portion 22 of the lever 20 is adapted as shown to rest upon the off-set portions 17 of the members 15. The end portion 23 of the lever 20 extends through a slot 24 in the rear portion of the before mentioned casing, 25 indicating said casing which is preferably of wood, the end 23 being provided with a suitable handle 26. It is obvious that by raising or drawing up the handle 26, the portion 22 of the lever depresses the members 15, thereby bringing all the slots 13 of the members 12 to register with the openings 8 of the wind-guide members 6 simultaneously,

and hence, all of the whistles are sounded at the same time.

Having described my invention what I claim as new and desire to secure by Letters Patent, is:

15 A chime whistle, in combination with a source of wind supply, said chime whistle comprising a plurality of whistle members, each having a tubular wind-guide member, there being one of said wind-guide members for each of said whistle members, a wind chamber, said wind-guide members being 40 secured in said wind chamber, valves for closing and opening the inner ends of said wind-guide members, a vertically disposed valve rod for each of said valves and each of said rods being provided with a horizontal 45 offset portion, springs on said rods for normally holding said valves in position to close the inner openings of said wind-guide members, a lever mounted on said wind chamber and having a portion resting upon said horizontal offset portions of said rods and adapted when properly operated to open all of said valves simultaneously, substantially as described.

20 In testimony whereof I have signed my name to this specification in the presence of two subscribing witnesses.

JOHN DONATH.
